UNITED STATES PATENT OFFICE.

HERBERT M. LOFTON, OF CHATTANOOGA, TENNESSEE.

GATE-VALVE.

1,106,723.

Specification of Letters Patent. Patented Aug. 11, 1914.

Application filed August 9, 1911. Serial No. 643,462.

To all whom it may concern:

Be it known that I, HERBERT M. LOFTON, a citizen of the United States, and a resident of the city of Chattanooga, county of Bradley, State of Tennessee, have invented an Improvement in Gate-Valves, of which the following is a specification.

My invention has reference to gate valves and consists of certain improvements which are fully set out in the following specification and shown in the accompanying drawings which form a part thereof.

The object of my invention is to provide a valve of this character with a construction which will permit the valve pieces to be closed easily upon their seats or opened with respect therefrom and without rubbing unduly against the contacting surfaces during the process of opening or closing the valve; and my object is further to provide in such valve a construction which will not obstruct the open area between the inlet and the outlet ports of the valve, when the valve is fully open.

My invention embodies in its construction a valve body having oppositely directed valve seats, and two independent valve pieces adapted to said seats, combined with independent cam devices, interposed between the valve pieces and movable to and from each other for forcing the valve pieces in opposite directions whereby they close upon their respective seats or are released therefrom, cam operating means for causing the said independent cam devices to be moved relatively to and from each other, and power applying means for operating the cam operating means last described for putting same into operation when closing the valve and out of operation when opening the valve.

My invention also comprehends the various features of construction and details which are all fully described hereinafter and more particularly defined in the claims.

My invention will be better understood by specific reference to the drawings, in which

Figure 1 is a longitudinal sectional elevation of a valve embodying my invention; Fig. 2 is a transverse sectional elevation of the same; Fig. 3 is a transverse sectional plan view of the same through the port area of the valve and with the inlet and outlets broken away; Fig. 4 is a plan view

of the valve and with the operating portion 55 in section; and Figs. 5, 6, and 7 are perspective views of details of the valve devices.

2 is the valve body and is provided with the inlet port 3 and outlet port 4, each of which may be furnished with bronze or other non-corroding metal seats 5. These ports through the seats are adapted to be closed by valve pieces or disk 6, 6, which are arranged to be moved vertically under the action of an operating screw stem or spindle 12 and connecting means. The body 2 of the valve is open at the top and covered with a bonnet 14 having at its upper part the stuffing box structure 13 through which the operating stem 12 extends. The stem 12 is supported in the bonnet so as to be capable of rotation but without vertical movement, but it is immaterial to my invention how this provision may be made.

7, 7, are two bronze parts for expanding 75 the disks or valve pieces 6 against their seats 5, 5. These parts 7, 7, have on each end three beveled cam faces 17, 8 and 17, which contact with inclined cam faces 18 on the disks 6 and with the cam faces 11 and 16 80 of the nut 10 and wedge body 15 respectively, and said parts 7, 7, are loose, but retained in relative position by their contacting cam faces aforesaid.

10 is a threaded stem nut in which the 85 stem 12 screws. The lower part of the stem nut is provided with the inclined cam portions 11.

15 is a lower wedge body having the cam portions 16. The threaded stem nut 10 has 90 opposite notched portions 20 having lower shoulders and upper shoulders and these notches are also provided with four lugs 22 and 23, which will be referred to later on. The valve disks 6, 6, are each provided with 95 two lugs 21, oppositely directed, and said lugs are undercut or slotted, as indicated at 21^a. These disks are each also provided with four inclined planes or cam surfaces, distributed about the center, as indicated 100 at 18.

By referring to Figs. 2, 4, and 6, it will be noted that the threaded stem nut 10 is provided with the four projecting lugs arranged in the notched portions 20 and indicated at 22 and 23. These are best shown in Fig. 6. These lugs are staggered, the lugs 22 and 23 being respectively arranged

at top and bottom of the notched portions 20 and at opposite edges; and moreover, this arrangement is followed in respect to each of the notched portions of the stem nut 10. 5 The purpose of these lugs will now be described.

In operation, it is necessary to provide some means for holding the upper ends of the valve disks together after they are removed from position against the valve seats, or more particularly, after they are moved into the valve bonnet 14. 10 This is accomplished in the following manner: The stem nut 10 is placed in position upon one of the disks 6 by slightly inclining the nut, so that the lugs 21 will enter into the recessed portions 20 on the nut; the said stem nut is then brought into a vertical position and parallel with the valve disk, which will cause two of 15 the lugs 22 and 23 to take hold in the slots 21^a on the said disk. Likewise, in placing the second valve disk in position, the same is slightly inclined until its lugs 21 enter the recessed portions 20 on the stem nut and 20 after this is done, the valve disk is then brought to a vertical position with the axis of the stem nut 10, which will cause the other two lugs 22 and 23 to take hold in the slots 21^a of this other disk. Therefore, as 25 30 the two valve disks 6, 6, are now in parallel position, and the stem nut 10 is in position between the two, it will be seen that by means of the four staggered lugs 22 and 23 and the slots 21^a on the two valve disks the latter are held together, allowing only sufficient play or lost motion to permit them being pressed against the valve seats when it is necessary to close the ports, or vice versa.

40 In operation, it will be seen that, by revolving the stem 12, the threaded stem nut 10 is lowered into the valve body, and the valve disks or pieces 6, 6, hanging upon the nut, are lowered with it to positions in front 45 of the ports. During this operation, the lower wedge body 15 comes in contact with the bottom of the valve body 2, as is indicated in Figs. 1 and 2, and at this time it is intended that the valve pieces or disks 50 shall be brought nearly opposite the valve seats. Any continued downward movement will cause the lower wedge body 15 to press upwardly, forcing the cam surfaces 16 thereof against the inclined surfaces 9 of the parts 7, 7, as shown in Fig. 2. This will cause the parts 7, 7, to move more slowly and 55 in a transverse direction to the movement of the disks and force their cam portions 8 in contact with the cam surfaces 11 on the stem 60 nut 10. It will thus be seen that the parts 7 being brought against the inclined surfaces 11 and 16 at their ends, will cause the wedges 17 to move outwardly from the line 65 of the valve stem and in a transverse direction relatively to the movement of the disks.

In doing this, the wedging surfaces 17 on the parts 7 will come in contact with the incline planes 18 on the valve pieces or disks 6 and thus press the said valve pieces or disks outwardly from each other, and 70 against the valve seats 5. It will also be seen that all of these wedging surfaces being co-dependent upon each other, will exert equal pressure against the four inclined planes on each of the valve pieces or disks, 75 and thereby insure that the valve disks will be pressed against the valve seats at absolutely equal pressure at four separate points of the circle of same. In opening the valve, the mechanism operates to release all pressure 80 against the disks before they are moved. This is done in the following manner: By rotating the valve spindle or stem in an opposite direction, the threaded stem nut 10 is moved upwardly, bringing the cam surfaces 85 11 out of contact with the cam surfaces 8. This immediately releases all pressure from against the valve disks; and a still further upward movement of the stem nut 10 will cause the lower shoulders of the notches 20 90 on the same to come in contact with the lower side of the lugs 21, on the valve disks, and continue to move them up, thus giving a clear passage through the valve.

Referring again to the valve mechanism; 95 I desire to state that the improved features of my invention embrace that of applying the pressure against the valve disk at four separate points, which is a very material improvement over those valves where the pressure is applied only in the center of the valve disk. By my construction, the springing of the valve pieces or disks is absolutely prevented, on account of applying the pressure at the four separate and equally divided points on the circle of the valve disk; and on account of the co-dependent feature of the wedging surfaces employed, this pressure is at all times equal at each of the four points at contact.

100 Another important feature of my invention is the means for holding the upper ends of the valve disks together by means of the lugs 22 and 23 working in the slots 21^a or upon the outer parts of the lugs 21. Heretofore, it has been necessary to provide some kind of links, requiring separate bolts or other means to hold the valve disks together and to the stem nut, and I overcome this difficulty in a very substantial and also a 110 very inexpensive manner.

115 From the foregoing, it will be observed that the parts 7 with their cams 8 and 9 and wedges 17 act as independent cam devices between the valve pieces or disks and are movable to and from each other for causing the disks to be moved to or from their seats; and likewise the stem nut 10 and wedge body 15 having their cam portions 120 co-operating with the parts 7 constitute cam op- 125 130

erating means for causing the independent cam devices to be moved relatively to each other.

I have shown my invention in the form I have found excellently adapted for commercial practice and while I prefer the construction shown, I do not restrict myself to the details, as they may be modified without departing from the spirit of the invention.

Having now described my invention, what I claim as new and desire to secure by Letters Patent, is:

1. In a gate valve, the body portion having oppositely directed inlet and outlet ports and valve seats arranged in alinement, combined with two valve disks for the respective valve seats each having a plurality of cam surfaces on opposite sides of a diametrical line, independent cam devices arranged between the disks and at all times out of operative contact with the body portion and each having four contacting parts for co-operating with a corresponding number of cam surfaces on the disks whereby said disks may be positively moved at their upper and lower portions simultaneously into contact with the valve seats, cam operating means independent of the cam devices and the body portion for causing the devices to be positively moved transversely to the movement of the disks both at top and bottom, and power applying means for operating the cam operating means.

2. In a gate valve, the body portion having oppositely directed inlet and outlet ports and valve seats arranged in alinement, combined with two valve disks for the respective valve seats each having a plurality of cam surfaces above and below a diametrical line, cam devices comprising independent parts out of operative contact with the body portion and movable to and from each other transversely to the direction of movement of the disks and having cam portions at upper and lower parts making contact with the cam surfaces of the disks above and below the diametrical line for forcing the disks apart and against their respective seats, cam operating means independent of the cam devices for causing the cam devices to be positively moved both at top and bottom transversely to the movement of the disks to make them positively operative upon the disks to the same extent both at the upper and lower parts thereof, and power applying means for actuating the cam operating means.

3. In a gate valve, the body having oppositely directed inlet and outlet ports and valve seats arranged in alinement, combined with two valve disks for the respective valve seats each having four cam surfaces, cam devices comprising a plurality of laterally movable parts each having cams on both ends and arranged between the disks and co-operating with the cam sur-

faces thereof for forcing the disks apart and against their respective seats equally at their upper and lower portions, cam operating means independent of the valve body for causing the cam devices to be moved to make them operative upon the disks, said means adjustably connected with the disks and also acting to hold the cam devices in position between the disks while permitting them to move laterally to and from said cam operating means, and power applying means for operating the cam operating means, the said cam devices being both movable laterally relatively to the power applying means and together with the cam operating means being simultaneously movable in opening or closing the valve and at all times in operative relation one to the other.

4. In a gate valve, the body having oppositely directed inlet and outlet ports and valve seats arranged in alinement, combined with two valve disks for the respective valve seats, cam devices arranged between the disks for forcing them apart and against their respective seats comprising two oppositely movable parts having at their ends wedge portions pressing upon the disks at a plurality of places about the center of the disks and also having inwardly directed inclined cam portions, cam operating means for causing the cam devices to be moved to make them operative upon the disks comprising two parts movable toward or from each other and movably connected with the disks and also having cam surfaces co-acting with the inwardly directed cam surfaces of the cam devices, one of these parts being arranged to have its movement arrested by the valve body, and power applying means for operating the other parts of the cam operating means.

5. In a gate valve, the combination of a body having oppositely directed inlet and outlet ports and valve seats arranged in alinement, with two valve disks for the respective valve seats said disks each having a plurality of cam surfaces and said valve disks each provided with suspending lugs having recesses parallel to the plane of the disks, cam devices comprising independent movable parts arranged between the cam disks and having cam surfaces co-operating with the cam surfaces upon the disks said cam devices movable toward or from each other transversely to the direction of movement of the disks in opening and closing the valve, cam operating means for causing the cam devices to be moved transversely to the movement of the disks to make them operative upon the disks said means being provided with recessed portions of greater vertical width than the thickness of the lugs on the disks and provided with lugs to engage the recesses of the lugs of the disks to hold the disks to the cam operating means,

2
and power applying means for operating the cam operating means.

6. In a gate valve, the combination of the body having inlet and outlet ports and valve seats therefor, with two valve disks for the respective valve seats said disks each having at their upper part inwardly directed lugs formed with vertical recesses between them and the disks, a nut provided with oppositely directed transverse recesses for receiving the lugs of the disks said recesses provided with lugs at their opposite ends to engage the recessed portions of the lugs of the disks and said lugs in each of the recesses of the nut being arranged at different elevations, and a screw for raising and lowering the nut and the disks supported thereby, the construction being such that the disks may be locked to the nut by turning them at an angle and sliding them into the recesses of the nut.

7. In a gate valve, an operating nut for the valve disks, which consists of a body part provided with oppositely directed transverse recesses 20 having at their diagonally opposite corners shallow lugs 22 and 23, combined with disks having lugs 21 formed with vertical recesses 21^a for engaging the oppositely directed recesses of the

nut back of the lugs of said recesses, and means for raising and lowering the nut.

8. In a gate valve, the body having oppositely directed inlet and outlet ports and valve seats therefor, combined with two valve disks for the respective valve seats, two independent parts between the disks and movable away from each other transversely to the direction of movement of the valve disks in closing the valve and coacting with the said disks for forcing them apart, means carried by the valve disks at their lower parts adapted to be supported by the bottom of the valve body and against which the independent parts are pressed to impart to them a transverse movement, means arranged at the upper part of the valve disks and between them for acting upon the independent parts for moving them transversely apart and also for supporting the disks, and an operating screw for raising and lowering the last mentioned means.

In testimony of which invention, I hereunto set my hand.

HERBERT M. LOFTON.
